BUNDLING MACHINE

Roy Neher, Clarence Center, N. Y., assignor to
National Gypsum Company, Buffalo, N. Y.

Application November 27, 1936, Serial No. 112,908

19 Claims.

(Cl. 216—9)

This invention relates to a method and apparatus for bundling or packaging slabs of material such as prepared wall board and the like.

It has heretofore been proposed to secure a number of gypsum or plaster wall surfacing units or a number of sections of plaster or gypsum lath by superposing or stacking several units upon each other and affixing an adhesive strip to the edges of the plurality of units. This is preferably accomplished by placing such strips on opposite sides of the group of units, the strip being of such width that it extends completely across the side edges of all of the units and has marginal portions which extend for some distance across the upper and lower faces of the upper and lower unit respectively, in the group.

In the preferred form only these marginally extending portions of the strip are coated with adhesive material and the intermediate portion 20 of the strip, which lies against the edges of the wall boards, is not so coated. By this method a convenient and sufficiently secure package is produced and yet one which may be readily broken when desired by merely slitting the strips 25 along the side edges of the wall board units.

An aim of the present invention is to provide an improved method and new apparatus for receiving a stacked group of units of the type described, insuring accurate superposition thereof, 30 and affixing the secured strips thereto.

In proceeding according to the principles of the present invention a stack containing a predetermined number of units is placed at the receiving end of my new apparatus and is thence fed automatically forwardly in the machine to a predetermined point where suitable instrumentalities become automatically effective to insure correct and accurate superposition of the slabs comprising the stack and firm abutment of the stack with its 35 immediately preceding stack. The accurately aligned pile of slabs then proceeds forwardly in the machine and the conveying mechanism is so arranged that successive piles of slabs are maintained in abutting end-to-end relationship.

45 While in such abutting end-to-end relation a continuous strip or ribbon of material, which may be paper or the like, is provided with a coating of an adhesive material and applied to each longitudinal side edge of the stacks continuously and 50 with marginal portions of the strip extending above and below the stacks of slabs. The projecting marginal portions of the strips are subsequently turned inwardly and caused to adhere to the upper and lower marginal portions of the 55 top and bottom slabs, respectively.

Following the application of the adhesive strip, a cutting mechanism, which is arranged to operate in timed relation with the movement of successive stacks or groups of slabs through the machine, severs the heretofore continuous strip at the point where the successive stacks or groups abut. This severance takes place substantially simultaneously at the side, top and bottom parts of the bundle and without interrupting the continuous movement of successive bundles through 10 the machine.

In the accompanying drawings I have illustrated suitable apparatus for proceeding according to the method of the present invention but it is to be understood that the form shown in the 15 drawings exemplifies merely my present preferred embodiment and that the present invention is not limited thereby or in any other way excepting as defined in the appended claims.

In the drawings, 20 Fig. 1 is a general side elevational view of the apparatus here involved;

Fig. 2 is a top plan view on a larger scale of the portion of the apparatus which lies at the feed end, that is, the end where successive stacks 25 of wall board or the like are manually introduced to the machine;

Fig. 3 is a similar view of the intermediate portion of the apparatus;

Fig. 4 is a similar view of that portion of the 30 apparatus lying at the delivery end of the machine, that is, at the point where the completed bundles or packages emerge and are removed from the apparatus;

Fig. 5 is a fragmentary end elevational view, 35 partly in cross section, looking from the forward end of the machine and illustrating the actuating elements for the pile-aligning means;

Fig. 6 is a transverse cross sectional view taken approximately on the line 6—6 of Fig. 4 and illustrating the fastening strip severing mechanism;

Fig. 7 is a fragmentary side elevational view of the means provided for causing the severing mechanism to become operative; and

Fig. 8 is a further fragmentary side elevational 45 view of this actuating mechanism with parts in cross section.

In the apparatus illustrated as my preferred embodiment I have provided a pair of parallel driving and conveying chains 10 which pass about a pair of sprockets 11 at the delivery end of the apparatus and a pair of sprockets 12 at the feed end. The pair of sprockets 11 are mounted upon and fixed for rotation with a shaft 13 which carries also a sprocket 14 which constitutes the 50 55

driving means for the conveying chain and the other moving instrumentalities of the apparatus.

The sprocket 14 may be connected, as by the driving chain 15, to any suitable source of power.

5 No such source of power has been illustrated in the drawings but I prefer to use an electric motor having associated therewith a suitable gear reduction unit of the usual constant ratio type, the gear reduction unit being connected in turn with 10 means for varying and controlling the speed of operation. This latter device may be a variable speed transmission of the Reeves type, with its driven shaft carrying a sprocket for association with the driving chain 15.

15 The upper reach of each conveying and driving chain 10 extends directly between its associated sprockets 11 and 12 and is supported at its under side by a track member 9, but the lower portion thereof passes about intermediate sprockets 20 16 and 17, the purpose of which will hereinafter appear, and a tensioning roller 18. The movement of the driving sprockets 11 is counter-clockwise as viewed in Fig. 1 so that the movement of the upper reach of each driving chain 10 is from 25 right to left, as viewed in that figure.

In commencing operation, the driving means is set in motion so that the conveying chains 10 move continuously and an initial stack or pile of slabs of predetermined number is manually placed 30 by the operator with one of its ends, the left hand end as viewed in Fig. 1, resting directly upon the conveying chain 10 and its other end resting upon a roller 19 mounted for free rotation upon a shaft 20 and disposed slightly above 35 the level of the upper reach of the conveying chains 10. The friction between the stack of slabs and the upper surface of the conveying chain 10 is sufficient to move the stack from right to left until its right hand end leaves the roller 19 and 40 drops until it rests completely upon the conveying chains 10.

During the dropping movement of the stack of slabs from the roller 19 to the conveying chains 10, the stack of slabs strikes a plate 21 which is 45 pivotally mounted as at 22. The plate 21 has a rearwardly extending arm 23 affixed thereto, which engages an extension spring 24 whose other end is anchored to a fixed part of the apparatus and which serves to resiliently hold the 50 plate 21 in the angular position illustrated in Fig. 1. Also affixed to the plate 21 is another plate portion 25 extending substantially at right angles thereto and disposed between complementary portions of the roller 19.

55 When the stack of slabs strikes the plate portion 21, which for the purpose of reducing friction is provided with a freely rotating roller 26 at its forward end, the plate portions 21 and 25 are rotated counterclockwise about the pivot 22 60 and the plate portion engages the rear edges of the slabs comprising the stack and tends to correct any misalignment of the several slabs comprising the stack.

65 The stack, in dropping, also strikes the upper end of a vertically disposed bar 27 which is illustrated in greater detail in Fig. 5. The bar 27 passes through an opening provided therefor in a plate member 28 which is part of the framework of the apparatus and is provided with a cam notch 29. The bar 27 is held in the position illustrated in Figs. 1 and 5 by means of a spring member 46 disposed about the lower portion of the bar 27 and arranged to permit resilient downward movement thereof.

A bell crank lever having horizontally and upwardly extending arms 30 and 31 respectively is mounted for free rotation on a pivot 32. The terminal portion of the arm 30 engages a notch in the bar 27 which provides a latch 33 and the 5 other arm 31 of the bell crank lever is provided with an opening for receiving the terminal portion of a rod or bar 34 which is associated with and by its movement opens and closes pneumatic valve means 35. The arm 31 is further provided with an extension spring 36 which is anchored at one end to a fixed part of the apparatus and constantly urges the bell crank lever in a clockwise direction about its pivot 32. In the position illustrated in Fig. 5, such clockwise 10 rotation is prevented by engagement of the arm 30 with the latch 33 and the valve 35 is in a closed position.

The initial downward movement of the bar 27 against the resilient resistance offered by the 20 spring member 46, causes counter-clockwise rotation of the bell crank lever, and the rod 34 is moved to the left as seen in Fig. 5 to cause opening of the valve 35. During completion of its downward movement, the cam notch 29 of the 25 bar 27 engages the side wall of the opening provided in the plate 28 and causes the bar 27 to move to the left, as seen in Fig. 5, a distance sufficient to release the arm 30 from the latch 33, whereupon the bell crank lever is moved clockwise 30 by the spring 36 until the valve 35 has again reached a closed position.

The resilient means 46 moves the bar 27 upwardly when pressure is removed from its upper end, whereupon the latch 33 again engages the 35 end of the arm 30 and the parts reassume the position illustrated in Fig. 5.

The momentary opening of the valve 35 establishes communication between a source of pneumatic or other fluid pressure and the interior 40 of a cylinder 37, Fig. 2. The surge of fluid pressure causes a piston 38 to move downwardly as seen in Fig. 2, against the action of a spring member 39. By means of a piston rod 40 the piston 38 is associated with a vertically disposed 45 plate member 41 which is located at one side of the apparatus and in a position slightly outside the normal path of travel of the stacks of slabs.

The momentary movement of the piston 38 to and fro in its cylinder 37 causes the plate member 41 to move into and out of engagement with the longitudinal side edges of the stack of slabs then passing along the conveying chains at this point and moves the several slabs temporarily 55 against a vertically extending stationary plate 42 provided at the opposite side of the stack of slabs and in this way causes the slabs of the stack to assume accurately aligned transverse positions with respect to each other.

The stack of slabs continues along the conveying chains 10 and passes beneath a feed roller 45 which is driven in a clockwise direction by a chain and sprocket drive 43 which takes its motion from the shaft carrying the sprocket 16.

At a time after the alignment of the stack has taken place, and preferably before the stack has passed completely beneath the driven roller 45, the next succeeding stack of slabs is placed in initial position by the operator with one of its ends upon the rear end of the first stack of slabs 70 and its other end resting upon the roller 19. The friction between the two stacks of slabs is sufficient to move the later placed stack along with the first stack until the forward edges of the later placed stack strike a stop plate 44 which 75

extends transversely of the apparatus adjacent to the feed roller 48. Relative sliding movement then takes place between the two stacks of slabs until the moment when the rear edges of the first placed stack pass beneath the stop plate 44, whereupon the forward end of the second placed stack drops to the driving chains 10 and is carried along thereby in the manner previously described for the first placed stack.

10 It is to be noted that in the case of all save the first stack, the longitudinal aligning of the several slabs is positively effected in that the aligning plate portion 28 engages the rear edges of a stack and urges the forward edges of that stack into abutting relation with the rear edges of the preceding stack.

As the successive stacks of slabs are carried along in abutting relation by the conveying chains 10 in cooperation with the driven roller 45 they pass beneath a series of idler rollers 50. These rollers are mounted with vertically movable journals so that they rest upon the upper surfaces of the stacks and hold them in intimate contact with the chains 10. Upon their emergence from between the idler rollers 50 and the chain 10 the stacks arrive at the position where the before mentioned fastening or packaging strips are applied to each of their longitudinal side edges.

20 This mechanism is illustrated in greater detail in Fig. 3 wherein the numeral 51 indicates continuous strips of paper of a width somewhat greater than the height of a stack of slabs and drawn from reels 52 located at each side of the apparatus. Each strip 51 passes through means 53 for applying an adhesive coating to its marginal portions on one surface. The means 53 are of conventional design and need not be described in detail herein.

30 After the strips leave the means 53 they are coated upon their upper surface and at their opposite marginal portions only with paste, glue, or other suitable adhesive. Each strip passes about an idle roller 54 having a vertical axis and thereafter by causing the strip to assume a position which is at right angles to its position when leaving the coating mechanism. The strip is then passed about a second freely rotating roller 55 which has likewise a vertical axis and is located closely adjacent and just outside the normal path of movement of the longitudinal side edges of the stacks as they pass through the apparatus.

35 A roller 56 at each side of the apparatus is carried by arms 57 which are pivotally mounted at 58. An extension spring 59 is secured at one of its ends to a fixed part of the apparatus and at its other end to one of the arms 57 to urge the arms 57 to rotate in a clockwise direction and thereby cause the roller to bear resiliently 40 against the strip 51 and cause it to assume a position in intimate contact with the longitudinal side edges of the stacks of slabs. The width of the strips 51 and the width of their coated marginal portions are such that when the strips are 45 in this position their coated marginal portions extend equal distances above and below the stack of slabs.

50 The previously applied portions of the strips 51, by their securement to the moving series of stacks, cause the strips 51 to be fed continuously from the supply reels 52 and over the several rollers at the same rate of movement as that of the stacks of slabs along the conveying chains 10.

55 A series of freely rotating rollers are provided

for turning the coated marginal portions of the strips 51 inwardly and to apply pressure thereto and cause adhesion between the upper and lower marginal portions of the strip and the upper and lower marginal portions of the stack of slabs 5.

In my preferred embodiment I provide two pairs of rollers 60, which may be of rubber or other resilient material and which are mounted for free rotation upon arms 61. The upper pair of arms 61 are mounted for pivotal movement in a vertical plane in blocks 130 by means of pivot pins 131. Arms 132 are mounted for joint pivotal movement with the arms 61. The arms 132 are offset in a vertical plane so as not to interfere with the rollers 60 15 and carry at their outer ends weights 133 which may be adjustable lengthwise of the arms 132 to vary their turning movement about the pivot 131. The weighted arm tends to rotate its associated roller carrying arm 61 about the pivot 20 131 and thereby move the roller 60 firmly against the upper surface of the stacks of slabs, the degree of pressure exerted by the upper rollers 60 being varied and controlled by the location of the weights 133 upon the arms 132. 25

The lower pair of rollers 60 are similarly provided with pivoted arms 61 (not shown) which are likewise pivotally positioned in blocks 130. In the case of the lower pivoted arms 61, the weighted arm associated therewith extends in an 30 opposite direction from the pivot 131 so that the tendency of the weighted arm, in the case of the lower pair of rollers, is to rotate the roller carrying arms 61 in such direction that the lower pair of rollers 60 are urged firmly 35 against the under surface of the stacks of slabs.

The four associated sets of blocks and arms are mounted for horizontal pivotal movement as at 62, and are provided with means for engaging arcuate slots 63 formed in plates 64 secured 40 to stationary portions of the machine to provide horizontal angular adjustment for each roll 60.

It will be seen that, by means of the weights 133 and the arms 132, all of the rollers 60 are urged uniformly against the four longitudinal marginal portions of the stacks of slabs regardless of 45 variations which may occur in the total thickness of a stack of slabs.

The rollers 60 are preferably so positioned angularly that they rotate in a plane at a substantial angle to the plane of the side edges of the stacks and hence produce a folding of the strips 51 and exert a substantial wiping action against the marginal portions of the stacks, as illustrated in Fig. 3, causing the marginal portions of the 55 strips 51 to be brought into intimate contact with the upper and lower surfaces of the stack as hereinbefore mentioned.

A second pair of rollers 65 are provided at each side of the machine which are likewise mounted 60 for free rotation but in a plane at a lesser angle to the plane of the side edges of the stack than in the case of the rollers 60. In the present instance the rollers 65 are mounted for free rotation upon rigidly secured shafts 66 which are angularly deformed to position the rollers 65 at a suitable angle.

As the now assembled stacks and strips 51 proceed through the apparatus they pass between additional sets of pressure rollers 67, 68, 69, successively. The rollers 67, 68, and 69 are similar in form and mounted similarly to the rollers 65 but at a still less angle to the side edges of the machine and further inwardly with respect to the stack of slabs so that they cause the marginal 75

edge portions of the strips to adhere closely to the surface of the stack of slabs.

The vertical disposition of the pairs of rolls 60, 65, 67, 68, and 69, located at each side of the machine is such that when the stacks pass between the rolls, they are elevated from the surface of the conveying chains 10, as appears in Fig. 6 and the stacks are pushed through this portion of the apparatus by succeeding abutting stacks extending back to the power driven feed rolls. In this way the maintenance of the abutting relationship of the successive stacks as they pass the strip-applying instrumentalities is positively insured.

15 After the strips 51 have been thus suitably secured to the side edges of the series of stacks, continued movement of the stacks brings them to a point where means are provided for severing the heretofore continuous strips at precisely the 20 point where the several stacks of slabs abut. The cutting mechanism, illustrated in Fig. 4 and in greater detail in Fig. 6, is adapted to operate without cessation of movement of the assembled stacks.

25 Referring now to Figs. 1, 7, and 8; I have provided at the delivery end of the machine and adjacent the driving sprockets 11 a lever 70 pivotally secured to a fixed part of the machine as at 20 11 and having an upwardly extending portion 72 which extends between the driving chains 10 and into the path of movement of the stacks of slabs. This extending part 72 is spaced at a distance equal to the length of one stack of slabs from the cutting mechanism which I have indicated 35 generally at 73 in Fig. 1 and is adapted to move about its pivot when engaged by the end of a stack of slabs so that its lower arm portion 88 moves to the right as seen in Figs. 1 and 7, thereby imparting a similar movement to a longitudinally extending bar 14 which is pivotally connected to the outer end of the arm 88.

40 Adjacent its other end the bar 14 has a cam notch 15 which engages the side walls of an opening 16 provided in the frame structure of the apparatus. At its outer end the bar 14 is notched to engage an upwardly extending arm 11 of a bell crank lever pivotally mounted at 18 and whose other arm portion 19 is provided with an extension spring tending to cause counterclockwise pivotal movement of the arm, which movement is normally prevented by engagement of the arm 11 with the notch in the bar 14.

45 A valve 81, of conventional design has a valve rod 82 which engages the arm 19 of the bell crank lever. When the parts are in the position illustrated in Fig. 8, the valve is closed and held in such closed position by a spring 83. When the bar 14 is caused to move to the right, as seen in Figs. 7 and 8, through impingement of a stack 50 of slabs against the upwardly extending arm 12, the bell crank lever is caused to rotate in a clockwise direction by the notch in the outer end of the bar 14 and against the resistance of the springs 80 and 83 and the valve 81 is thereby caused to 55 open momentarily.

60 Further movement of the bar 14 to the right causes it to move upwardly by reason of the engagement of the cam notch 15 with the side wall of the opening 16 until its outer end is moved out 65 of engagement with the arm 11 of the bell crank lever, whereupon the bell crank lever returns, under the impetus of the springs 80 and 83, to the position illustrated in the drawings and fluid movement through the valve 81 is again interrupted.

The opposite sides of the valve 81 are connected respectively to the source of air pressure hereinbefore mentioned and to a fluid operating mechanism for cutting means 13 which will hereinafter be described in detail.

5

When it is desired to package or bundle stacks of slabs of different lengths, the lever 70 is pivoted at other points provided therefor upon the framework of the apparatus and bars 14 of different lengths are utilized. The bar 14 may be 10 formed sectionally so that parts thereof may be removed or added to vary its effective length.

15 After the lever 70 has been rotated by contact with the edge of a stack of slabs, and the stack has passed thereover, the stack engages a 20 pair of curved straps 86 which are anchored at their ends to the framework of the machine and whose center portions are bowed outwardly so that they extend above the surface of the conveying chains 10 as indicated in Fig. 1. The 25 stacks then move upwardly on the bowed portions of the straps 86 sufficiently to permit the lever 70 to resume its normal position with its upwardly extending arm 72 in position to be acted upon by the next succeeding front edge of a stack of 30 slabs. At this time the cutting mechanisms 73 have acted to sever the binding strips 51 in a manner which will hereinafter be described and the finished bundle stack of slabs may be 35 manually removed from the machine or may be 40 pushed out by the following bundle until they overbalance and are deposited into suitable delivery devices.

We refer now to Figs. 4 and 6 wherein is illustrated one of the pair of cutting mechanisms 35 45 heretofore generally designated 73. Each cutting mechanism is carried by a block 90 whose lower end is provided with a threaded extension for engaging in a gland nut 91 which serves to rigidly connect the block 90 to a bushing 92 50 which is freely rotatable in an opening provided in a plate 93. The plate 93 is positioned upon a stationary plate 94 which forms part of the framework of the machine and is secured therefor to transverse sliding movement by means of 55 suitable screw and slot connections, not shown.

The transverse movement of the plate 93 with respect to the plate 94 is controlled by the adjusting screw 95. The adjusting screw 95 has an enlarged portion 96 which bears against one 60 face of a bearing block 97 carried by the plate 94 and a collar 98 retains the screw 95 against axial movement. The outer threaded end of the screw 95 engages a complementary threaded opening in a block 99 carried by the slidable plate 65 93. The manner in which rotation of the adjusting screw 95 causes relative transverse sliding movement of the plate 93 with respect to the plate 94, for adjustment of the former, will now be apparent.

60 Secured to one face of the block 90 is a member 100 which in the present instance is provided with three cylindrical openings, each carrying a piston member 101 having a piston rod 102, which extends through a bore provided in the block 90 and engages a cutter holding member 103 disposed on the opposite side thereof. A compressible spring 104 may be provided between one or more of the pistons 101 and the opposed face of the block 90 to normally retain the pistons 70 at their left hand limit of movement as viewed in Fig. 6. The ends of the cylinders which lie opposite the block 90 are closed by a member 105.

The bushing 92 is connected at its lower end to a pressure conduit 106 and when the valve 75

member illustrated in Fig. 8 is caused to be momentarily opened by engagement of a stack of slabs with the arm 72, fluid communication is established between the source of fluid pressure and the interior of the cylinders through the bushing 92, a passage 107 provided in the block 90, a passage 108 provided in the member 100 and a passage 109 in the member 105, the latter having branch passages 110 leading to the interiors of the several cylinders.

A pair of arms 112 are pivotally mounted adjacent the upper and lower outer corners of the cutter holding member 103. The arms 112 are urged toward each other by leaf springs 113 carried by the cutter holding member 103 and their movement toward each other is definitely limited by abutment of the arms with portions of the cutter holding member 103. As illustrated in Fig. 6, the arms 112 are at their minimum distance 20 from each other.

Carried by the outer end of each arm 112 is a cutting wheel or rowel 114 and a vertically extending cutting knife 115, which is preferably notched as illustrated, extends intermediately of 25 the arms 112 and is rigidly secured to the cutter holding member 103.

It will be seen that the admission of fluid under pressure to the cylinders through the passageways 110 will cause the pistons 101, the 30 ton rods 102 and the cutter holding block, together with the various instrumentalities carried thereby, to move toward the row of joined stacks passing through the machine, whereupon the cutting wheels 114 ride up onto the upper 35 and lower surfaces of the strip 51 and are pressed thereagainst by the springs 113 to effect severance of the strip 51 at these points. Just prior to the inward limit of movement of the cutting disks 114, the vertically extending knife 115 engages the vertical portion of the strip 51 and effects severance thereof.

As has been stated, the bushing 92 serves to mount the entire cutting mechanism pivotally with respect to the plate 93 and means are provided for normally maintaining the cutting mechanism in a predetermined position with respect to its pivotal mounting. These means include a strap member 116 having pivotal connection at one of its ends with the upper end 50 of the block 90 at a point concentric with the lower bushing 92 as at 117, and at its other end secured to the plate 93 as at 118.

Carried by the strap 116, intermediately of its ends, is a second strap 119 which carries an adjusting screw 120 having suitable means for locking with respect to the strap 119 and having its outer end in abutting engagement with the side of the block 100 when the cutting mechanism is in normal position with respect to its pivoted 60 mounting, that is, when the cutting disks 114 and the knife 115 lie in a plane perpendicular to the direction of movement of the stacks of slabs through the machine. The cutting mechanism is normally maintained in this position with the block 100 abutting the adjusting screw 120 by means of a spring member 122 which is anchored at one of its ends to the member 105 of the cutting mechanism and at its other end to an offset terminal portion of the strap 119.

The timing of the operation of the cutting mechanism is such, by reason of the location of the arm 72, that the cutting instrumentalities engage the strip 51 at a point where successive stacks of slabs abut. The movement of the 70 knives toward the stacks and the resultant cut-

ting operation is abruptly accomplished and any forward movement occurring during the cutting operation is negligible. Any forward movement of the stacks which does occur is compensated for by a slight pivotal movement of the entire 5 cutting mechanism, which is caused to rotate against the resistance of the spring 122 because of the engagement of the cutting wheels 114 with the strip 51 and between the abutting stacks of slabs.

The retrograde movement of the cutting mechanism, under the impetus of the spring 104, need not be so quickly accomplished since further pivotal movement of the cutting mechanism may take place against the resistance of the spring 122 until the cutting wheels 114 completely leave 15 the stacks of slabs, whereupon the cutting mechanism will be immediately restored to its normal position by the spring member 122.

Another set of two pairs of resilient rollers 125 is provided beyond the cutting mechanism 20 and these rollers are similar in form and disposition to the rollers 67, 68, and 69. The rollers 125 serve to additionally urge the now severed strips 51 against the upper and lower surfaces of the stacks of slabs and also tend to correct any 25 loosening of the strips 51 which may have occurred adjacent the ends of the stacks during the operation of the cutting mechanism.

I claim:

1. Apparatus for bundling flat slabs of material 30 comprising means for moving a series of stacks of slabs in a continuous, substantially direct path, means for initially supporting each stack serially in a position above the immediately preceding stack in such manner that the stack so supported 35 is brought into said moving series at the time that the preceding stack has passed from beneath said supported stack, other means actuated by the movement of said stack into said series for correcting misalignment of said stack, and means for 40 joining the several slabs comprising each stack to each other for handling and shipment.

2. Apparatus for bundling flat slabs of material comprising means for moving a series of stacks of slabs in a continuous substantially direct path, 45 means for preliminarily supporting such stacks successively in a position above the immediately preceding stack with one of the ends of said supported stack resting upon the preceding stack in such manner that the supported stack will drop 50 to a substantially abutting relation with respect to the preceding stack as said preceding stack passes from beneath the supported stack and means rendered operable by the dropping of said supported stack for engaging against the edges 55 of the slabs comprising said stack at the end opposite the abutting end to urge the stack into firm abutting relation with the preceding stack.

3. Apparatus for bundling flat slabs of material comprising means for moving the series of 60 stacks of slabs in a continuous substantially direct path, means for preliminarily supporting such stacks successively in a position above the immediately preceding stack with one of the ends of said supported stack resting upon the preceding 65 stack in such manner that the supported stack will drop to a substantially abutting relation with respect to the preceding stack as said preceding stack passes from beneath the supported stack, and other means operable by the dropping of said supported stack into abutting relation for engaging the longitudinal side edges of the slabs composing the stack for insuring accurate transverse alignment and positioning of the slabs in the stack.

4. Apparatus for bundling flat slabs of material comprising means for moving the series of stacks of slabs in a continuous substantially direct path, means for preliminarily supporting such stacks successively in a position above the immediately preceding stack with one of the ends of said supported stack resting upon the preceding stack in such manner that the supported stack will drop to a substantially abutting relation with respect to the preceding stack as said preceding stack passes from beneath the supported stack, means rendered operable by the dropping of said supported stack for engaging against the edges of the slabs comprising said stack at the end opposite the abutting end to urge the stack into firm abutting relation with the preceding stack to insure accurate longitudinal alignment and superposition of the individual slabs composing the stack and other means operable by the dropping of said supported stack into abutting relation for engaging the longitudinal side edges of the slabs composing the stack for insuring accurate transverse alignment and superposition of the slabs in the stack.
5. An apparatus for bundling flat slabs of material comprising means for moving a series of stacks of slabs in a continuous, substantially direct path, means maintaining the series of stacks in abutting relation, means for securing a continuous strip of binding material to the longitudinal marginal portions of said series of stacks, and means for severing said strips at the points of abutment of the several stacks, said severing means comprising cutting elements positioned for periodic transverse movement against the sides of said series of stacks, movable means for said cutting elements permitting longitudinal movement thereof and resilient means for normally maintaining said cutting elements in a predetermined longitudinal position but permitting longitudinal movement of the cutting means with the series of stacks when said cutting means are in engagement with said binding strip.
6. Apparatus for bundling flat slabs of material comprising means for moving a series of stacks of slabs in a continuous, substantially direct path, means maintaining the series of stacks in abutting relation, means for securing a continuous strip of binding material to the longitudinal marginal portions of said series of stacks, and means for severing said strip at the points of abutment of the several stacks, said severing means being mounted for pivotal movement on a vertical axis, and means for moving said severing means transversely in timed relation with the movement of the stacks for engaging said severing means against the longitudinal side edges of the stacks at their points of abutment for severing said binding strip, and resilient means for normally retaining said severing means in a predetermined position with respect to its pivotal mounting but permitting pivotal movement thereof against the resistance of said resilient means when said severing means is in engagement with the moving stacks or the binding strip, said resilient means being adapted to return the severing means to normal position when engagement of the severing means with the stacks and binding strip is discontinued.
7. In combination with apparatus having means for continuously conveying articles in a substantially direct path, cutting mechanism positioned adjacent the path of movement of said articles and means for periodically moving said cutting mechanism transversely against said

articles for performing a severing operation, said cutting mechanism being mounted for pivotal movement about an axis substantially at right angles to the path of movement of the articles and resilient means for normally retaining said cutting mechanism in a predetermined position about said axis whereby severing engagement between the cutting mechanism and said articles may cause pivotal movement of said cutting mechanism against the resistance of the resilient means, said cutting mechanism being returned to normal position by the resilient means when the severing engagement is interrupted.

8. In combination with apparatus having means for continuously conveying articles in a substantially direct path, cutting mechanism positioned adjacent the path of movement of said articles and means for periodically moving said cutting mechanism transversely against said articles for performing a severing operation, said cutting mechanism being normally retained against longitudinal movement with respect to the path of movement of said articles by spring means, said cutting mechanism being adapted to move longitudinally with said articles and against the resistance of the spring means when the cutting mechanism is in severing engagement with said articles.

9. Apparatus for bundling flat slabs of material comprising means for moving a series of stacks of slabs in a continuous path, means disposed adjacent the path of the stacks for applying means for securing the individual slabs of each stack to each other, means for initially supporting each stack serially in a position above the immediately preceding stack with one of its ends resting upon the preceding stack and its other end supported by said means, said means having anti-friction bearing contact with said stack whereby the stack is moved longitudinally with said preceding stack, means for arresting the movement of the stack at a predetermined point whereby the preceding continuously moving stack moves out from under said first mentioned stack whereupon the latter drops into the plane of the preceding stack in substantially abutting relation, and means actuated by the dropping of said stack for moving the several slabs comprising said stack into accurate vertical alignment.

10. Apparatus for bundling flat slabs of material comprising means for moving a series of stacks of slabs in a continuous path, means disposed adjacent the path of the stacks for applying means for securing the individual slabs of each stack to each other, means for initially supporting each stack serially (in a position above the immediately preceding stack) with one of its ends resting upon the preceding stack and its other end supported by said means, said means having anti-friction bearing contact with said stack whereby the stack is moved longitudinally with said preceding stack and means actuated by the dropping of said stack for engaging the back of the stack and urging said stack intimately against the preceding stack.

11. Apparatus for bundling flat slabs of material comprising means for moving a series of stacks of slabs in a continuous path, means disposed adjacent the path of the stacks for applying means for securing the individual slabs of each stack to each other, means for initially supporting each stack serially (in a position above the immediately preceding stack) with one of its ends resting upon the preceding stack and its

- other end supported by said means, said means having anti-friction bearing contact with said stack whereby the stack is moved longitudinally with said preceding stack, means for arresting 5 the movement of the stack at a predetermined point whereby the preceding continuously moving stack moves out from under said first mentioned stack whereupon the latter drops into the plane of the preceding stack in substantially 10 abutting relation, means actuated by the dropping of said stack for engaging the back of the stack for urging the stack against the preceding stack and means actuated by the dropping of said stack for moving the several slabs comprising 15 said stack transversely into accurate vertical alignment.
12. Apparatus for bundling flat slabs of material comprising means for supporting a series of stacks of slabs in a substantially straight line, 20 power driven means adjacent one end of said supporting means for engaging said stacks successively and positively moving said series of stacks toward the opposite end of the apparatus through the abutting relationship of said stacks 25 which is maintained by said power driven means, means intermediate said power driven means and said opposite end of the apparatus for applying continuous adhesive strips to the opposed longitudinal side edges of said series of stacks with 30 said stacks in abutting relationship, and means acting in timed relation with the passage of individual stacks through the apparatus for severing said strips adjacent the abutment of successive stacks.
13. Apparatus for bundling flat slabs of material comprising means for moving a series of stacks of slabs in a continuous, substantially direct path, means maintaining the series of stacks in abutting relation, means for securing a continuous strip of binding material to the longitudinal marginal portions of said series of stacks, and means for severing said strip at the points of abutment of the several stacks, said last mentioned means comprising a hydraulic cylinder disposed horizontally and transversely of the path of movement of said slabs and having a piston and a piston rod extending in a direction toward the longitudinal side edges of said stacks, cutting means carried on said piston rods, and valve means for admitting fluid to said cylinder in timed relation with the movement of successive stacks through the apparatus for moving said cutting means against said stacks at their points of abutment through movement of said 55 piston and piston rod.
14. Apparatus for bundling flat slabs of material comprising means for moving a series of stacks of slabs in a continuous, substantially direct path, means maintaining the series of stacks in abutting relation, means for securing a continuous strip of binding material to the longitudinal marginal portions of said series of stacks, and means for severing said strip at the points of abutment of the several stacks, said last mentioned means comprising a hydraulic cylinder disposed horizontally and transversely of the path of movement of said slabs and having a piston and a piston rod extending in a direction toward the longitudinal side edges of said stacks, cutting means carried on said piston rods, and valve means for admitting fluid to said cylinder in timed relation with the movement of successive stacks through the apparatus for moving said cutting means against said stacks at their points of abutment through movement of said piston 60 and piston rod, said cutting means being mounted for movement in a generally longitudinal direction and resilient means for normally retaining said cutting means against such movement, whereby engagement of the cutting means with the moving stacks is accommodated by corresponding movement of the cutting means against the resistance of the resilient means.
15. Apparatus for bundling flat slabs of material comprising means for moving a series of stacks of slabs in a continuous, substantially direct path, means maintaining the series of stacks in abutting relation, means for securing a continuous strip of binding material to the longitudinal marginal portions of said series of stacks, and means for severing said strip at the points of abutment of the several stacks, said last mentioned means comprising a hydraulic cylinder disposed horizontally and transversely of the path of movement of said slabs and having a piston and a piston rod extending in a direction toward the longitudinal side edges of said stacks, cutting means carried on said piston rods, and valve means for admitting fluid to said cylinder in timed relation with the movement of successive stacks through the apparatus for moving said cutting means against said stacks at their points of abutment through movement of said piston and piston rod, said cylinder and cutting means being mounted for joint movement and resilient means for normally retaining said cylinder and cutting means in predetermined position, whereby engagement of the cutting means with the moving stacks is accommodated by corresponding movement of the cutting means against the resistance of said resilient means.
16. Apparatus for bundling flat slabs of material comprising means for moving a series of stacks of slabs in a continuous, substantially direct path, means maintaining the series of stacks in abutting relation, means for securing a continuous strip of binding material to the longitudinal marginal portions of said series of stacks, and means for severing said strip at the points of abutment of the several stacks, said last mentioned means comprising a hydraulic cylinder disposed horizontally and transversely of the path of movement of said slabs and having a piston and a piston rod extending in a direction toward the longitudinal side edges of said stacks, cutting means carried on said piston rods, and valve means for admitting fluid to said cylinder in timed relation with the movement of successive stacks through the apparatus for moving said cutting means against said stacks at their points of abutment through movement of said piston and piston rod, said cutting means being mounted for movement in a generally longitudinal direction and resilient means for normally retaining said cutting means against such movement, whereby engagement of the cutting means with the moving stacks is accommodated by corresponding movement of the cutting means against the resistance of the resilient means.
17. Apparatus for bundling flat slabs of material comprising means for moving a series of stacks of slabs in a continuous, substantially direct path, means maintaining the series of stacks in abutting relation, means for securing the marginal portions of continuous strips of binding material to the longitudinal marginal 70
- 75

portions of the upper and lower surfaces of said series of stacks with the intermediate portion of said strip extending across the longitudinal, vertically extending edges of the stacks, and means for severing said strip at the points of abutment of the several stacks, said severing means being mounted for pivotal movement on a vertical axis, and means for moving said severing means transversely in timed relation with the movement of the stacks for engaging portions of said severing means against the longitudinal side edges of the stacks and other portions of said severing means against the upper and lower marginal portions of said stacks at their points of abutment for severing said binding strip, and resilient means for normally retaining said severing means in a predetermined position with respect to its pivotal mounting but permitting pivotal movement thereof against the resistance of said resilient means when said severing means is in engagement with the moving stacks or the binding strip, said resilient means being adapted to return the severing means to normal position when engagement of the severing means with the stacks and binding strip is discontinued.

18. Apparatus for bundling flat slabs of material comprising means for moving a series of stacks of slabs in a continuous, substantially direct path, means maintaining the series of stacks in abutting relation, means for securing the marginal portions of continuous strips of binding material to the longitudinal marginal portions of the upper and lower surfaces of said series of stacks with the intermediate portion of said strip extending across the longitudinal, vertically extending edges of the stacks, and means for severing said strip at the points of abutment of the several stacks, said severing means comprising means mounted for movement toward and away from the longitudinal side edges of the stacks in timed relation with the passage of stacks through the apparatus and comprising a vertically extending cutting means for severing the inter-

mediate portion of said strip at the points of abutment of the stacks and cutting rollers positioned above and below said vertically extending cutting means and extending forwardly therefrom in the direction of movement of the severing means, said cutting rollers being adapted to move across the upper and lower marginal portions of said stacks at their points of abutment for severing the marginal portions of said strip. 5

19. Apparatus for bundling flat slabs of material comprising means for moving a series of stacks of slabs in a continuous, substantially direct path, means maintaining the series of stacks in abutting relation, means for securing the marginal portions of continuous strips of binding material to the longitudinal marginal portions of the upper and lower surfaces of said series of stacks with the intermediate portion of said strip extending across the longitudinal, vertically extending edges of the stacks, and means 10 for severing said strip at the points of abutment of the several stacks, said severing means comprising means mounted for movement toward and away from the longitudinal side edges of the stacks in timed relation with the passage of stacks through the apparatus and comprising a vertically extending cutting means for severing the intermediate portion of said strip at the points of abutment of the stacks and cutting rollers positioned above and below said vertically extending cutting means and extending forwardly therefrom in the direction of movement of the severing means, said cutting rollers being adapted to move across the upper and lower marginal portions of said stacks at their points of abutment for severing the marginal portions of said strip, said cutting rollers being movable resiliently away from each other and being normally spaced at a distance less than the height of the stacks, whereby the cutting rollers are urged resiliently against said marginal portions and automatically adjust their spacing to variations in height of the stacks. 20 25 30 35 40

ROY NEHER.

CERTIFICATE OF CORRECTION.

Patent No. 2,113,549.

April 5, 1938.

ROY NEHER.

It is hereby certified that error appears in the printed specification of the above numbered patent requiring correction as follows: Page 6, second column, lines 57 and 58, and lines 73 and 74, claims 10 and 11 respectively, strike out the parentheses; and that the said Letters Patent should be read with this correction therein that the same may conform to the record of the case in the Patent Office.

Signed and sealed this 31st day of May, A. D. 1938.

Acting Commissioner of Patents.

- portions of the upper and lower surfaces of said series of stacks with the intermediate portion of said strip extending across the longitudinal, vertically extending edges of the stacks, and means 5 for severing said strip at the points of abutment of the several stacks, said severing means being mounted for pivotal movement on a vertical axis, and means for moving said severing means transversely in timed relation with the movement of 10 the stacks for engaging portions of said severing means against the longitudinal side edges of the stacks and other portions of said severing means against the upper and lower marginal portions of 15 said stacks at their points of abutment for severing said binding strip, and resilient means for normally retaining said severing means in a pre-determined position with respect to its pivotal mounting but permitting pivotal movement there-of against the resistance of said resilient means. 20 when said severing means is in engagement with the moving stacks or the binding strip, said resilient means being adapted to return the severing means to normal position when engagement of the severing means with the stacks and binding strip is discontinued. 25

18. Apparatus for bundling flat slabs of material comprising means for moving a series of stacks of slabs in a continuous, substantially direct path, means maintaining the series of stacks in abutting relation, means for securing the marginal portions of continuous strips of binding material to the longitudinal marginal portions of the upper and lower surfaces of said 30 series of stacks with the intermediate portion of said strip extending across the longitudinal, vertically extending edges of the stacks, and means for severing said strip at the points of abutment of the several stacks, said severing means comprising means mounted for movement toward and away from the longitudinal side edges of the stacks in timed relation with the passage of stacks 35 through the apparatus and comprising a vertically extending cutting means for severing the intermediate portion of said strip at the points of abutment of the stacks and cutting rollers positioned above and below said vertically extending cutting means and extending forwardly therefrom in the direction of movement of the severing means, said cutting rollers being adapted to move across the upper and lower marginal portions of said stacks at their points of abutment for severing the marginal portions of said strip. 40

19. Apparatus for bundling flat slabs of material comprising means for moving a series of stacks of slabs in a continuous, substantially direct path, means maintaining the series of stacks in abutting relation, means for securing the marginal portions of continuous strips of binding material to the longitudinal marginal portions of the upper and lower surfaces of said series of stacks with the intermediate portion of said strip extending across the longitudinal, vertically extending edges of the stacks, and means for severing said strip at the points of abutment of the several stacks, said severing means comprising means mounted for movement toward and away from the longitudinal side edges of the stacks in timed relation with the passage of stacks 45 through the apparatus and comprising a vertically extending cutting means for severing the intermediate portion of said strip at the points of abutment of the stacks and cutting rollers positioned above and below said vertically extending cutting means and extending forwardly therefrom in the direction of movement of the severing means, said cutting rollers being adapted to move across the upper and lower marginal portions of said stacks at their points of abutment for severing the marginal portions of said strip. 50
